JIG SAW PUZZLE BOARD

Charles L. Wallace, 11440 Court St., No. 1,
Stanton, Calif. 90680

Filed Dec. 2, 1974, Ser. No. 528,702

Term of patent 14 years

Int. Cl. D21—01

U.S. Cl. D34—15 M

FIG. 1

FIG. 2

FIG. 6

FIG. 3

FIG. 7

FIG. 4

FIG. 5

FIG. 1 is a perspective view of a jig saw puzzle board showing my new design;

FIG. 2 is a top view thereof;

FIG. 3 is a side view thereof;

FIG. 4 is a bottom view thereof;

FIG. 5 is an end view thereof;

FIG. 6 is a sectional view taken of a fragment of the jig saw puzzle board on line 6—6 of FIG. 2; and

FIG. 7 is a pictorial enlarged view of a fragment of my new jig saw puzzle board showing one of the ridged decorations.

I claim:

The ornamental design for a jig saw puzzle board, as shown.
